UNITED STATES PATENT OFFICE.

JOHANN NICOLAUS DEPPERT AND ADOLF SEELIG, OF MANNHEIM,
GERMANY.

FOUR-COLOR PLATEN-PRESS.

SPECIFICATION forming part of Letters Patent No. 727,307, dated May 5, 1903.

Application filed November 11, 1902. Serial No. 130,915. (No model.)

To all whom it may concern:

Be it known that we, JOHANN NICOLAUS DEPPERT and ADOLF SEELIG, subjects of the Emperor of Germany, residing at Printworks, 5 Mannheim, Grand Duchy of Baden, Germany, have invented certain new and useful Improvements in Four-Color Platen-Presses, of which the following is a specification.

The object of the present invention is to print with several colors in succession in the same manner as in platen-presses. This is accomplished by the use of a vertically-rotatable prismatic bed, each side of which, besides the form, has a color apparatus for supporting that printing-face which for the time being is momentarily opposite the form which is being printed.

In the drawings, Figure 1 is a side elevation. Fig. 2 is a horizontal section over the 20 rotating device of the bed. Fig. 3 is a front view with the platen removed and partly in section at the upper part of the bed.

The wheel *a* gears in the usual manner with a pinion *b* on the driving-shaft and produces 25 through the link *c* the pressure of the platen against the form *d* in the bed. The bevel-pinion *e* on the driving-shaft *f* gears with the bevel-wheel *g* and operates the pawl *h* through the arm *i*, so that at one half-revolution of the 30 bevel-wheel *g* the ratchet-wheel *k*, and consequently the bed, is caused to make a quarter-revolution, while during the other half-revolution the pawl *h* slides back into the next tooth, when the bed remains stationary. 35 Simultaneously with the pressure of the platen the inking takes place of the type opposite to that which is being printed. This is accomplished through the link *l* (attached to the wheel *a* and hinged 40 to the arm *n*, secured to the shaft *m*) slightly turning the shaft *m*, when the arm *o* (whose length is automatically adjusted by a spring) is caused to engage with its hooked end into the hook *p* of the inking apparatus and pulls the latter down over the 45 type. On the rise of the arm *o* (and by the operation of the balance-weight *u*) the inking apparatus again goes to the top.

The inking-rollers *r'*, *r²*, *r³*, and *r⁴* of the 50 inking apparatus are spring-mounted in the usual manner on rising and falling slides *q*.

In order that the inking of the type may

take place evenly and the ink may not all be left on the upper part, swells *s* are provided on both the slides of the two lower inking-rollers *r³* and *r⁴*, which keep them from the upper part of the type and cause them to only ink the lower part, while the inking of the upper part is effected by the two upper rollers *r'* *r²*. The four color devices are suspended 60 from rolls by chains *t*, attached to balance-weights *u*. Each balance-weight is provided with a drop-hook which on the rise of the weight engages with the toothed wheel *w*, secured to the ink-distributing plate *v* and intermittently turns the latter, and with it the plate, while on the descent of the weights *u* the drop-hook clears itself and passes the tooth-wheel without acting on it. The gripper *x* is held firmly on the paper by a spring 70 during the printing of the four colors and is only lifted after the four colors have been printed by a cam-like surface at the corner of the bed, (after the fourth color,) up and down which a bowl on one arm of an L-lever 75 is caused to travel, so as to operate the toothed segment on the other arm, thereby rotating a pinion gearing therewith. This pinion is on the axis of the gripper, and as it turns in one direction or the other the gripper is depressed or raised.

In order to construct a press for more than four colors, the prism which forms the bed is made with a correspondingly greater number of sides.

We claim—

A multicolor platen-press comprising a bed having a plurality of faces, with means for turning the said bed, a platen associated with said bed, vertically-movable inking-rollers to 90 ink the forms on the said bed, a counterbalance-weight for the said rollers, an ink-distributing plate, a toothed wheel in connection therewith and means for operating the toothed wheel and ink-distributing plate from the 95 counterbalance-weight, substantially as described.

In witness whereof we have hereunto set our hands in presence of two witnesses.

JOHANN NICOLAUS DEPPERT.

ADOLF SEELIG.
